[57] CLAIM

The ornamental design for a baby stroller, as shown and described.

DESCRIPTION

FIG. 1 is a front and left side perspective view of a baby stroller showing my new design;

FIG. 2 is a rear and right side perspective view of a second embodiment of the baby stroller, the sole difference between the first embodiment being in the different front wheels;

FIG. 3 is a rear and left side perspective view of FIG. 1 with a translucent canopy removed; and,

FIG. 4 is a left perspective view of FIG. 3.

The bottom and interior of the design are plain and unornamented.
